A-FRAME DOG HOUSE

Edwin C. Leonard, 1212 Camrose Road,
Richmond, Va. 23229

Filed Feb. 14, 1967, Ser. No. 5,803

Term of patent 14 years

(Cl. D12—2)

FIG-1

FIG-2

FIG-3

FIG-5

FIG-6

FIGURE 1 is a perspective view of an A-frame dog house made in accordance with my invention;

FIGURE 2 is a side elevational view of the dog house of FIGURE 1;

FIGURE 3 is a front elevational view of the dog house of FIGURE 1;

FIGURE 4 is a rear elevational view of the dog house of FIGURE 1;

FIGURE 5 is a bottom view of the dog house of FIGURE 1; and

FIGURE 6 is a cross sectional view taken along lines 6-6 of FIGURE 2.

I claim:

The ornamental design for an A-frame dog house, substantially as shown.
